United States Patent Office

Des. 187,188
Patented Feb. 9, 1960

187,188

CHECK DESK

Evalin Schrift-Gross and Albert Milton, Chicago, Ill.

Application January 23, 1958, Serial No. 49,377

Term of patent 7 years

(Cl. D33—7)

Fig. 1 is a perspective view of a check desk showing our new design; and

Fig. 2 is an end view of the check desk of Fig. 1.

The sides not shown are of substantially the same configuration as the corresponding sides which are shown.

We claim:

The ornamental design for a check desk, substantially as shown and described.
